INTERNAL COMBUSTION ENGINE

William A. Beck, Milwaukee, Wis.

Application January 5, 1946, Serial No. 639,335

2 Claims. (Cl. 123—73)

1

The present invention relates in general to improvements in internal combustion engines and relates more specifically to improvements in the construction and operation of four-cycle opposed-cylinder engines of the internal combustion type.

The primary object of this invention is to provide an improved four-cycle opposed-cylinder internal combustion engine which is simple and compact in construction, and which is also highly efficient in operation.

It has heretofore been proposed to provide a four-cycle two-cylinder opposed type of internal combustion engine wherein the crank case was utilized for high charge compression purposes, but this particular type of engine has not proven satisfactory primarily because of difficulties encountered in starting due to high pressure acting simultaneously on both pistons, and also because of the relatively large bulk of the prior assemblages. It has also been proposed to provide such an internal combustion engine without crank case compression, and wherein none of the explosive mixture was permitted to enter the crank case, and this modified type was objectionable because the main pistons could not be utilized to introduce the successive fuel charges into the cylinders and also because it eliminated the possibility of utilizing the fuel as a carrier for crank case lubrication. Neither of these prior types of four-cycle engines made any provision for limiting the crank case volumetric capacity, and while the crank case compression type facilitated the injection of the fuel under high pressure it was hard to start, whereas the other type required the provision of special fuel injection means and also introduced complications in lubrication. Both of these prior types of four-cycle two-opposed-cylinder internal combustion engines were therefore relatively objectionable and never became popular within the trade.

It is therefore a more specific object of my invention to provide an improved four-cycle internal combustion engine of the two-opposed-cylinder type, in which all working parts may be amply supplied with lubricant together with the fuel or explosive mixture, which may be readily and reliably started, and which still utilizes the main pistons for the purpose of positively introducing the explosive mixture into the cylinders.

Another specific object of this invention is to provide a simple, compact, light-weight and inexpensive internal combustion engine which is adapted for diverse uses, especially in cases

2

where a light but powerful unit is required, as for example in aeronautics and boat propulsion.

These and other specific objects and advantages of my invention will be apparent from the following detailed description.

A clear conception of the features constituting my present improvement, and of the construction and operation of a typical engine embodying the invention may be had by referring to the drawing accompanying and forming a part of this specification wherein like references characters designate the same or similar parts in the various views.

Fig. 1 is a diagrammatic longitudinal vertical section through a typical four-cycle two-opposed-cylinder internal combustion engine showing the left piston beginning its intake or suction stroke, and the right piston being subjected to its power stroke by explosion of a previously compressed fuel charge.

Fig. 2 is a similar view of the same engine showing the left piston beginning its compression stroke, and the right piston starting on its exhaust stroke.

Fig. 3 is another similar view of the assemblage showing the left piston being subjected to its explosion or power stroke, and the right piston beginning its intake or suction stroke.

Fig. 4 is still another similar sectional view of the same engine, showing the left piston starting on its exhaust stroke, and the right piston beginning its charge compression stroke, and

Fig. 5 is a diagrammatic longitudinal horizontal section through the engine showing the limited volumetric capacity of the crank case.

While the invention has been shown and described herein as having been applied diagrammatically to a four-cycle two-opposed-cylinder internal combustion engine wherein the explosive mixture is utilized as a carrier for the crank case lubricant, it is not my desire or intention to unnecessarily restrict the scope or utility of the improved features by virtue of this limited disclosure.

Referring to the drawing, the improved four-cycle two-opposed-cylinder internal combustion engine shown therein, comprises in general a main frame 7 forming a crank case 8 having left and right cylinders 9, 10 disposed on opposite sides thereof but slightly out of axial alignment; a main shaft 11 journaled for rotation in the frame 7 and having a pair of crank pins 13 and crank discs 14 revolvable within the crank case 8; left and right main pistons 15, 16

reciprocable within the cylinders 9, 10 respectively, and being connected to the adjacent crank pins 13 by means of connecting rods 17; a fuel mixing device or carburetor 18 communicable with the crank case 8 past an explosive mixture supply valve 19; open conduits or passages 20, 21 of limited size connecting the crank case 8 with the outer ends of the cylinders 9, 10 respectively; an intake valve 22 interposed directly between each cylinder 9, 10 and its fuel supply passage 20, 21; and an exhaust valve 23 for spent gasses associated with the outer end of each cylinder 9, 10.

The main frame 7, cylinders 9, 10, and pistons 15, 16 are preferably formed of light but durable material and may be cooled in any well known manner, and the volume of the crank confining chamber or crank case 8 is preferably reduced to a minimum by filling excess space with relatively large and heavy discs 14 which provide considerable flywheel effect. The fuel supply device or carburetor 18 may be of any suitable type adapted to supply gaseous fuel mixed with and acting as a carrier for lubricating oil in sufficient quantities to maintain the crank pins 13, pistons 15, 16 and all of the valves amply lubricated at all times; and the supply and intake valves 19, 22 should be so timed that the pistons 15, 16 will merely act as a pump to positively inject the successive fuel charges into the cylinders 9, 10 without materially compressing the gasses confined within the crank case 8. While the conduits or passages 20, 21 should preferably be of limited size, they should not be restricted to such extent that they necessitate high compression of the fuel in order to transfer the charges from the crank case 8 to the cylinders 9, 10; and the valves 19, 22, 23 may be of any suitable well known type and may be controlled by a timer of suitable construction also well known to those skilled in the art.

When the improved four-cycle internal combustion engine has been properly constructed, assembled and adjusted, it may be readily started by initially rapidly revolving the main shaft 11 a few turns in the usual manner, and such starting is greatly facilitated due to the fact that no high compression is ever established within the crank case 8. After the engine has been thus started, the following cycle of operations will be rapidly repeated. When the pistons 15, 16 recede from the outer ends of their strokes the valve 22 of the left cylinder 9 will be opened and the valve 22 of the right cylinder 10 as well as both exhaust valves 23, will be closed as shown in Fig. 1. The charge of explosive mixture thus confined within the right cylinder 10 should then be ignited and the resulting explosion will drive the piston 16 inwardly and will rotate the shaft 11 while causing the simultaneously receding piston 15 to draw a charge of fuel into the left cylinder 9 past the open valve 22.

As the pistons 15, 16 reach the inner ends of their strokes, the previously open valve 22 of the left cylinder 9 will be closed and the exhaust valve 23 of the right cylinder will be opened, so that when the pistons begin their outward strokes as in Fig. 2, the left piston 15 will compress the fuel charge confined within the cylinder 9 while the right piston 16 will expel the exhaust gasses past the open valve 23 of the cylinder 10. During the next inward stroke of the pistons 15, 16, both valves of the left cylinder 9 will be closed, and only the intake valve 22 of the right cylinder 10 will be open as depicted in Fig. 3, whereupon the charge of fuel confined within the left cylinder

9 will be exploded to force the piston 15 inwardly and to impart rotation to the shaft 11, while the right piston 16 is drawing another fuel charge into its cylinder 10.

When the pistons 15, 16 reach the inner ends of their strokes as a result of this explosion, the valves 22, 23, of the right cylinder 10 will be closed and only the exhaust valve 23 of the left cylinder 9 will be opened, as shown in Fig. 4, and the piston 16 during its next outward stroke will compress the fuel charge confined within the cylinder 10, while the outwardly moving opposed piston 15 will expel spent gasses from the cylinder 9 past the open exhaust valve 23. Rotating impulses will thus be imparted to the shaft 11 in rapid succession and the speed of rotation may be readily controlled or regulated in a well known manner, and the supply valve 19 may be automatically opened and closed in properly timed relationship to the opening and closing of the intake valves 22, in any desired and well known manner.

From the foregoing detailed description it will be apparent that my present invention provides a simple, compact, and highly efficient four-cycle opposed-cylinder internal combustion engine which may be conveniently started. Reliable and easy starting of the improved engine is greatly facilitated by avoiding high pressures within the crank case 8 at all times, as the pistons 15, 16 act merely as low pressure fuel displacement members during their return strokes but do serve to positively inject the fuel charges into the cylinders 9, 10 during the intake strokes thereof. By thus utilizing the pistons rapid injection of full charges of fuel into each cylinder, is assured without resorting to the use of special pumps or other apparatus for insuring such full fuel charges when operating at high speed. The admission of the fuel to the crank case 8, however permits lubricant to be supplied to the crank pin and shaft bearings with the fuel; and by utilizing the fuel as a lubricant carrier, the pistons, cylinders and valves may all be effectively lubricated without resorting to complicated lubricating mechanisms. It is also preferable to reduce the volumetric capacity of the crank case 8 and of the conduits 20, 21, as much as possible in order to increase the efficiency or pumping action of the pistons 15, 16 under low pressure, to a maximum extent; and such reduction in size also provides greater compactness in the motor as a whole. The pistons 15, 16 thus serve as effective super-chargers for positively introducing the fuel into the cylinders without necessarily resorting to special and more complicated supercharging mechanisms, but do not undesirably hinder or obstruct the starting effort. The present improvement has proven highly satisfactory and successful in actual use, and provides a light but powerful internal combustion engine adapted for diverse uses, which may be manufactured and sold at very low cost.

It should be understood that it is not desired to limit this invention to the exact details of construction and operation, herein shown and described, for various modifications within the scope of the appended claims may occur to persons skilled in the art.

70 I claim:

1. A four-cycle internal combustion engine comprising, a pair of cylinders separated by an intervening crank case and each having a piston reciprocable therein, a pair of opposite throw 75 cranks each connected to one of said pistons by

a connecting rod and being simultaneously revolvable to reciprocate said pistons in opposite directions within said cylinders, said crank case being only of sufficient size as to snugly confine said cranks so as to reduce the volumetric capacity of the confining space to minimum clearance requirements, and means for causing said pistons to positively urge gaseous fuel charges at approximately atmospheric pressure from within said crank case into said cylinders during in-strokes of the pistons.

2. A four-cycle internal combustion engine comprising, a pair of cylinders separated by an intervening crank case and each having a piston reciprocable therein, a pair of opposite throw cranks each connected to one of said pistons by a connecting rod and being simultaneously revolvable to reciprocate said pistons in opposite directions within said cylinders, said crank case being only of sufficient size as to snugly confine said cranks so as to reduce the volumetric capacity of the confining space to minimum clearance requirements, and a series of valves operable to cause said pistons to positively urge gas-

eous fuel charges at approximately atmospheric pressure from within said crank case into said cylinders during each in-stroke of both pistons.
